GUIDE FOR USE IN DRIVING SHEET PILING

August H. Hausler, Chicago, Ill.

Original application May 14, 1934, Serial No. 725,491. Divided and this application April 25, 1935, Serial No. 18,152

10 Claims. (Cl. 61—60)

This invention relates to an improved guide member for use in driving sheet piling, such as the interlocking sheet piling which is commonly employed in forming breakwaters, coffer-dams and the like, and the present application is a division of my co-pending application, Serial No. 725,491, filed May 14, 1934, now Patent 2,057,947 of October 20, 1936, in which there is described and claimed an improved method of driving sheet piling to form such structures, according to which sheet piles are interlocked with each other to form a plurality of separate panels or sections which are then moved to the place where they are to be driven and spaced apart along their lateral edges in vertical positions to be connected by intermediate connecting sheet piles preliminary to driving all of the piles into the bed of the river or harbor in which the structure is to be formed. In the practice of that improved method, the separate panels or sections of sheet piling are spaced apart by clamps or spacing devices which form the subject-matter of my co-pending application, Serial No. 17,401, filed April 25, 1935, and these spacing devices which detachably engage the lateral edges of the panels are removed prior to or during the process of driving the intermediate connecting sheet piles which secure adjacent panels together.

The principal object of the present invention is to provide an improved guide member adapted to be mounted upon the upper ends of adjacent sheet piles which are spaced apart and which are to be connected by an intermediate sheet pile and the function of the guide member is to direct the intermediate sheet pile into proper interlocking engagement with the spaced piles to be connected thereby at the commencement of the operation of driving the intermediate pile. A further object of the invention is to provide an improved guide member adapted to be detachably mounted upon the upper end of a sheet pile for directing the lateral edges of two sheet piles into proper interlocking engagement with each other when one pile is driven with respect to the other. Still another object of the invention is to provide an improved guide member having parts for detachably engaging a pile and having a projecting guide portion adapted to coact with one of the interlocking parts of an adjacent sheet pile when the latter pile is brought into engagement with the pile in which the guide member is mounted. Other objects relate to various features of construction and arrangement which will appear more fully hereinafter.

55 The nature of the invention will be understood

from the following specification taken with the accompanying drawings, in which one embodiment is illustrated.

In the drawings,

Fig. 1 shows an enlarged vertical section through a portion of a breakwater or the like illustrating the method of driving sheet piling according to the invention of applicant's said original application and illustrating the use of the improved guide member of the present invention; 5

Fig. 2 shows an enlarged horizontal section on the line 2—2 of Fig. 1, illustrating two of the guide members of the present invention which are employed for guiding a connecting pile when this pile is driven into interlocking engagement 10 with the end piles of two adjacent sections or panels; 15

Fig. 3 is a perspective view of one of the improved guide members of the present invention; and 20

Fig. 4 shows an elevation of one of the guide members illustrated in Fig. 2, together with portions of the adjacent sheet piles.

In Fig. 1 of the drawings there is shown a portion of a breakwater 15 which is being constructed according to applicant's invention by driving a plurality of separate panels or sections of connected sheet piles to form a series of connected enclosures into which rock 19 or other ballast is filled after the piles have been driven. At the 25 left of Fig. 1, there is shown a portion of the side wall 20^c of one of the sections of the breakwater and this side wall is connected to an opposite side wall by a transverse wall 20^b, all of these walls being formed of similar sheet piles which interlock with each other at their edges. At the junction of the side wall section with the transverse wall section, there is a connecting sheet pile 21 of triangular cross-section having a flange which is adapted to interlock with the side wall of the 30 next adjacent breakwater section, which is shown as being in the process of construction, by the driving of two adjacent panels 20^e each formed of a series of interlocking sheet piles 16. Each pile 16 comprises a longitudinal flat web 16^a 35 united at each edge with a curved portion 16^b, as shown in Fig. 2, and these curved portions are united with integrally formed hook members 16^c and guard members 16^d. With this construction, there is provided at each edge of each pile a longitudinal groove or recess 16^e which is adapted to be engaged by the hook member of the next adjacent, and reversely arranged, pile 16 when 40 two piles are interlocked with each other. 45

In order that the piles 16 forming a panel 20^e 50

may be held in assembled relationship with respect to each other while the panel is being moved from the place of assembly to the place where the piles are to be driven, and to hold the panel in the desired shape, the various piles making up the panel are preferably secured to a channel-shaped bar 22 which is provided with a series of projecting wedge-bolts 22^a adapted to engage apertures 16^f which are formed in the webs of the piles, preferably adjacent the upper ends thereof. The bar 22 is adapted to seat against the webs of alternate sheet piles and when the wedge-bolts 22^a, which are preferably welded to the bar, have been inserted through the apertures 16^f, the wedges or keys 22^b are inserted through slots in the wedge-bolts, thus holding the sheet piles in place against the bar. The keys 22^b are preferably carried by chains 22^c which are attached to the upper flange of the bar 22 so that the keys are always in readiness for use. After a section or panel of interlocking sheet piling has been put in place, the keys 22^b are removed and the bar 22 is taken away from the piles preliminary to driving the piles.

Assuming that a new section of the breakwater is about to be formed, a floating raft 23 is placed against the end wall 20^b of the breakwater section which has previously been formed and the panels 20^e which are to constitute one side wall of the next breakwater section are placed in position against the edge of the raft, which has a horizontal cross-section corresponding to the shape of the breakwater section to be formed. This raft is secured to the previously formed breakwater section and serves as a platform upon which the workmen may stand during the process of driving the piles which make up the panels 20^e. When the panels 20^e have been formed, they are placed in position along the edge of the raft with their lower edges resting on the bottom and one or more of the piles which are not secured to the bar 22 may be driven slightly into the bed of the river or harbor to assist in holding each panel in place. When these panels 20^e are thus put in place along the edge of the raft, they are spaced apart from each other and from the corner piles 21 distances which are each equal to the width of one sheet pile 16 and they are held in this spaced relation around the raft by means of spacing devices or clamps 30 which are detachably secured to the lateral edges of adjacent sheet piles and which constitute the subject-matter of my said co-pending application Serial No. 17,401, filed April 20, 1935. After the spacing devices 30, which may be formed of cast, forged or rolled steel, are put in place to space adjacent wall sections or panels from each other and to space the inner side panel from the adjacent corner pile 21, the wall sections 20^e conform to the curvature of the edge of the raft 23 and all of the piles 16 occupy vertical positions in readiness for driving. Before these piles are driven, the detachable spacing devices 30 are removed and may be placed upon the raft. As the spacing devices 30 are detached and removed from the spaced sheet piles which have been connected thereby, another sheet pile 16 is inserted in interlocking engagement with the spaced sheet piles which have previously been connected by those spacing devices and one such sheet pile is inserted in the space between the edge of one panel and the adjacent corner pile 21. This operation requires the elevation of the intermediate or connecting sheet piles 16, which are to occupy these spaces, until their lower ends are capable of en-

gaging the longitudinal grooves of the sheet piles which are to be connected by them. In Fig. 1, these connecting sheet piles are shown by dotted lines and one of these sheet piles is shown as occupying an elevated position which permits its lower end to be passed into interlocking engagement with the panels 16 which constitute the edge piles of the two adjacent panels 20^e.

To facilitate the passing of a connecting pile into interlocking engagement with two adjacent spaced piles, a pair of guide members 40, constructed according to the present invention, are detachably mounted upon the upper ends of the previously positioned piles for guiding the new pile into interlocking engagement with the spaced piles. These guide members 40 are of the form shown particularly in Figs. 2, 3 and 4 and include right-hand and left-hand guide members for engaging the opposite edges of the same sheet pile. Each guide member comprises a horizontal bar 40^a having a handle 40^b projecting from the upper side thereof and having enlargements 40^c at its ends from which project downwardly two pairs of spaced legs 40^d. At one end, the bar 40^a is provided with a hook-shaped member 40^e projecting from one of the enlargements 40^c and constructed to conform to the shape and curvature of the guard members 16^d which are formed along the edges of the sheet pile 16. The guide members 40 are put in place on the upper ends of the previously assembled and spaced piles 16 with the legs 40^d straddling the portions 16^a and 16^b of the sheet piles, as shown in Fig. 2. Since the guide members 40 of each pair are constructed as right-hand and left-hand members, the guide fingers 40^e on opposite guide members will be directed toward each other and they will be positioned directly above the guard members of the sheet piles and will form stops against which the hook members 16^e of the piles to be driven may be placed, as shown in Figs. 2 and 4. Then, upon moving the intervening sheet pile downwardly, the portions 40^e of the guide members 40 serve as guides to direct the hook members 16^e of the pile into engagement with the slots 16^f of the spaced piles at the ends of the panels which have previously been positioned. When the connecting sheet pile has been driven downwardly from the position shown by dotted lines at the upper right-hand portion of Fig. 1 until it interlocks with the sheet piles at the edges of adjacent panels, it will form a permanent connection between those panels and all of the sheet piles of these panels may then be driven into the bed of the river or harbor in which the breakwater or other structure is being formed.

Although one form of the invention has been shown and described by way of illustration, it will be understood that it may be constructed in various other embodiments coming within the scope of the appended claims.

I claim:

1. The combination with a sheet pile having a portion of its edge adapted to interlock with another sheet pile, of a guide member having parts straddling the end of said first-named sheet pile and having a flange extending adjacent said edge of said first-named sheet pile to guide said other sheet pile into engagement with said edge portion.

2. The combination with a sheet pile having a hook portion and a guard portion at its edge, of a guide member mounted on the end of said pile and having a part aligning with and con-

forming to the curvature of said guard portion.

3. The combination with a sheet pile, of a guide member having a pair of spaced legs to embrace opposite sides of a sheet pile and having a guide member extending longitudinally therefrom.

4. A guide member for sheet piling comprising a bar adapted to rest upon the end of the sheet pile, members extending from said bar to straddle the sheet pile on opposite sides thereof, and a guide finger projecting longitudinally from the end of said bar to receive within it a portion of an adjacent sheet pile.

5. The combination with a sheet pile having a hook portion and a curved guard portion at its edge, of a guide member in the form of a bar resting on the end of said pile with parts thereof extending downwardly on opposite sides of the pile and with a longitudinally extending curved guide flange conforming to the curvature of said guard portion of the pile and adapted to direct the hook portion of another pile into the space between the hook portion and the guard portion of said first named pile.

25 6. The combination with a sheet pile, of a guide member comprising a bar adapted to rest on the upper end of a sheet pile and having legs spaced apart to extend downwardly on opposite sides of said sheet pile, said bar having 30 extending longitudinally therefrom a curved guide flange adapted to register with an underlying part of said sheet pile.

7. The combination with a sheet pile having a hook portion and a guide portion at its edge, of a guide member mounted on the end of said pile and having a part aligning with and conforming to the shape of one of said portions. 5

8. The combination with a sheet pile having an integral portion at its edge adapted to interlock with a mating integral portion at the edge of another sheet pile, of a guide member detachably mounted on said first-named pile and having a part conforming to the shape of a part of said integral portion of said first-named pile and adapted to be engaged by a part of the mating integral portion of the second-named pile to guide said integral portion of the second-named pile into interlocking engagement with the integral portion of said first-named pile. 10 15

9. The combination with a sheet pile, of a guide member having a plurality of pairs of spaced legs adapted to embrace opposite sides 20 of a sheet pile and having a guide finger extending horizontally therefrom adjacent an edge of the pile.

10. The combination with a sheet pile having a hook portion and a guide portion at its edge, of a guide member mounted on the end of said pile and having a part projecting longitudinally therefrom to a point above and in alignment with and conforming to the shape of one of said portions. 25 30

AUGUST H. HAUSLER.
